DESIGN FOR A SET OF JEWELLED ALPHABET PINS

Harry Reinstein, New York, N. Y.

Application March 26, 1941, Serial No. 99,897

Term of patent 3½ years

To all whom it may concern:

Be it known that I, Harry Reinstein, a citizen of the United States, residing at New York, in the county of the Bronx and State of New York, have invented a new, original, and ornamental Design for a set of Jeweled Alphabet Pins, for which the following is a specification, reference being had to the accompanying drawing, forming part thereof, wherein—

Fig. 1 is a plan view of a set of jeweled alphabet pins, showing my new design; and,

Fig. 2 is a perspective view of one of the letters of the set of jeweled alphabet pins, namely the letter A.

I claim:

The ornamental design for a set of jeweled alphabet pins, substantially as shown.

HARRY REINSTEIN.
